CLAIM

We claim the ornamental design for a cap for an insertion device, substantially as shown and described.

DESCRIPTION

FIG. 1 is a perspective view of a cap showing my new design; FIG. 2 is a top view thereof; FIG. 3 is a side view thereof; FIG. 4 is a front view thereof; FIG. 5 is a rear view thereof; FIG. 6 is a side view thereof; and, FIG. 7 is a bottom view thereof.

The cap protects the tip of an insertion device from deformation or damage.
